UNITED STATES PATENT OFFICE.

GEORGE F. WENNAGEL AND CARROLL THOMAS, OF BALTIMORE, MARYLAND.

CAR-HEATING APPARATUS.

Application filed April 1, 1926. Serial No. 99,137.

The invention relates to heating apparatus for electrically propelled cars.

The principal object of the invention, generally stated, is to provide a car heating apparatus embodying resistance elements located within the car and capable of being employed in place of some or all of the usual starting rheostats whereby the heat generated by the passage of current through the resistance elements may be utilized for heating the interior of the car instead of being wasted by dissipation into the atmosphere as is the case when the ordinary exteriorly arranged rheostats are used.

Unless some means is provided for conserving the heat generated by the passage of current through the rheostats, there is a great loss of energy and, obviously, a tremendous expense which should be avoided. It has been calculated that the energy consumed by the rheostats constitutes as high as 16% or more of the total amount used and it is readily understood that this is a dead loss under ordinary conditions where the exteriorly arranged rheostats are used.

It is with the above facts in view that we have designed the present invention which has for an important object the provision of heaters adapted to be mounted in any desired locations within a car, as for instance beneath or near the seats, the heaters embodying resistance elements which may be grouped in any desired or necessary manner to possess approximately the same ohmic resistance as the exteriorly located rheostats, the apparatus or system embodying means whereby the exterior rheostats or the said resistance elements may be selectively used, depending upon the season of the year or the temperature of the atmosphere.

Another object of the invention is to provide a car heating system or apparatus in which it will be unnecessary to provide auxiliary heaters or any other than the ones embodying the resistance elements which are usable in lieu of the conventional exteriorly located rheostats, at least under ordinary circumstances, there being however, no restriction as to the employment of additional ones if found necessary or advisable, as for instance in very cold climates.

A still further object of the invention is to provide a heating apparatus embodying a very simple switch arrangement or control device readily operable by the motorman or

conductor for throwing the resistance elements of the heaters, or the exterior rheostats into the circuit, as the case may be, it being clear that the use of the latter would probably be preferable in summer or at any other time when the temperature of the atmosphere is sufficiently moderate to render heat unnecessary.

Yet another object of the invention is to provide a heating apparatus for electric cars of the type equipped with motors at the front and rear, the arrangement of the circuits and apparatus being such as not to interfere in any way with the customary energization and action of the motors, it being furthermore unnecessary to change the controller mechanism, or the usual wiring other than by adding thereto.

Another object of the invention is to provide a car heating apparatus embodying resistance elements located within the car and so connected and arranged with respect to the usual circuits and a manually operable control means that any desired number of the resistance elements may be thrown into the circuit to replace only a part of the exteriorly located rheostat devices, it being consequently possible to modify or temper the heating action as would be desirable in mild weather.

A still further object of the invention is to provide a heater which may conveniently be arranged to replace the ordinary foot rest, the heater possessing certain mechanical features which will permit it to be mounted in this manner, the arrangement being furthermore such that the individual heaters are grounded for the purpose of providing a clear path in case of a short circuit, danger of fire or personal injury from this cause being consequently eliminated.

An additional object of the invention is to provide an electric car heating apparatus of this character which may be installed at small cost and without making any material alterations in the car structure, and which will effect a valuable saving in energy, thereby reducing the cost of operation.

To the attainment of the foregoing and other objects and advantages as will hereinafter appear, the invention preferably consists in the construction, combination and arrangement of parts to be more fully described and claimed, and illustrated in the accompanying drawings in which:

Figure 1 is a diagram showing the arrangement of the resistance elements in the heating devices with respect to the usual circuits, 5

Figure 2 is a fragmentary vertical cross section through a car showing a convenient manner of mounting the heaters,

Figure 3 is a detail elevation of one of the heaters, parts being broken away and in section,

10 Figure 4 is an end elevation of one of the heaters,

Figure 5 is an end elevation of a slightly modified form of heater.

Referring to the drawings in detail the 15 numerals 1, 2, 3, 4, 5, 6 and 7 designate the conductors of the usual wiring system which lead from the controller and with which are connected the motors, not shown, and with the respective ones of which are connected 20 leads 8, 9, 10, 11, 12, 13 and 14 which, under ordinary circumstances, connect with the resistances or units 15, 16, 17, 18 and 19 which constitute the starting rheostat or rheostats which are customarily located exteriorly of 25 the car body, generally beneath the same. The manner in which the successive resistance units of the rheostat device may be cut into or out of the motor circuit is immaterial to a proper understanding of the present invention especially as it is well known that the 30 control is effected by means of the ordinary controller operated by the motorman.

In carrying out the present invention we 35 provide any desired number of suitably constructed heaters adapted to be mounted at any preferred locations within the car body, each of the heaters embodying any desired number of resistance elements or units 20 connected in any desired manner, it being preferable that the resistance elements of several 40 heaters be connected to form groups represented in the diagram by the numerals 21, 22, 23, 24 and 25, the number of groups conveniently corresponding to the number of 45 resistance units in the exterior rheostats. To preserve the same action regardless of whether the exteriorly arranged or interiorly located resistances be used, it is desirable that the ohmic resistance of the units or elements in the groups 21, 22, 23, 24 and 25 correspond to that of the units 15, 16, 17, 18 and 19.

In order that the motorman or other operator 55 may use either set of resistances at will, depending upon temperature conditions or other circumstances, we provide switch means which we have illustrated, diagrammatically, as conveniently consisting of two separate switches 26 and 27 which may be of 60 the double throw knife type, the number of poles of course depending upon the number of groups of resistances. In at least one standard form of control there are two exteriorly located rheostats, one of which includes 65 three units and the other of which in-

cludes two units, as illustrated in the diagram though it should be understood that there is absolutely no restriction in this respect as the invention is equally capable of application to other systems or arrangements. For 70 the sake of illustration the switch 26 is shown as having four poles with which the respective leads 8, 9, 10 and 11 are connected, it being clear that the usual direct connection of these leads to the exterior resistances must 75 be broken. This switch may further include contacts 28, respectively connected with the successive units 15, 16 and 17, and other contacts 29 with which connect conductors 30 connected with the successive groups 21, 22 80 and 23 of the resistance elements in the heaters. The switch 27 is in the present instance shown as having three poles and includes contacts 31 respectively connected with the successive units 18 and 19 of the exterior rheostat. The switch 27 also includes contacts 32 from which lead conductors 33 connected with the respective groups 24 and 25 of resistance elements in the heaters. Any equivalent switch mechanism or structure may of 85 course be provided.

In the operation, it will be seen that when the switches 26 and 27 are thrown to engage the contacts 28 and 31 the exteriorly arranged resistances 15, 16, 17, 18 and 19 will 90 be thrown into the control circuit so that the action thereof will be the same as usual and this would be done whenever it is undesirable to supply heat to the interior of the car, as for instance in summer time. When the 100 switches are thrown to engage the contacts 29 and 32 the outside rheostats are cut out entirely and the groups 21, 22, 23, 24 and 25 of inside resistances are thrown into the control circuit so that when the controller is 105 operated in the usual manner for regulating the motor speed the groups of resistance units in the heaters will have current pass therethrough in exactly the same manner as when the exterior rheostats are used. It will be 110 observed that all the heat from the resistances is utilized, thereby obviously effecting a great saving in energy consumption as it is probable that these heaters will be entirely sufficient to effect heating of the car, except 115 possibly in very severe weather or in unusually cold climates, in which case the rheostat heaters may be supplemented by auxiliary heaters of a regular type. If desired, one 120 of the switches may be thrown to include the exterior rheostats in the circuit while the other is thrown to include only a few groups of the inside resistances in the circuit and in this way it is apparent that the heating effect 125 may be controlled in accordance with temperature conditions.

From a mechanical viewpoint, the heaters themselves may be of any desired construction suitable for the purpose. Nevertheless, we have, in Figures 2, 3 and 4 illustrated a 130

specially designed heater which will be found extremely advantageous for the purpose, it being possible to mount these heaters at any desired location, but preferably to take the place of the usual foot rests located below the seats. Referring to these figures in detail, we have shown the heater as comprising an elongated body 34 of metal, preferably aluminum, this body being capable of formation as a casting. To increase the heating surface the body is preferably ribbed or corrugated throughout at least the major portion of its length as shown at 35. Any desired number of the resistance units 20 may be arranged within the body which may be cored out as indicated at 36, or cast solidly around the unit or units, or otherwise formed for the reception thereof. In the form illustrated in Figure 4 there are two heating units 20 closed which have their terminals 37 connected with metal bridge strips 38 to which the leads are connected as indicated, the purpose of this arrangement being to connect the two units in parallel. A single unit may be provided as in Figure 5. The exact nature of the unit is immaterial as it may be specially designed or may be one of a variety on the market.

In order that the heater may be mounted in a simple manner, it is shown as provided at one end with a projection 39 adapted to fit within a socket 40 commonly provided in the seat pedestal or bracket 41 for mounting one end of the usual foot rest, which must of course be removed. The other end of the body of the heater is represented as of a somewhat shell-like construction to provide a chamber 42 within which the terminal connections, bridge strips, etc., are enclosed, this chamber being subsequently preferably filled with some sort of insulating material which will embed the parts. This end of the body is preferably provided with laterally extending apertured ears or lugs 43 so that it may be bolted in place against the metal plate 44 located against the inside of the car body near the floor. This same end of the heater is provided with a ledge 45 which engages upon the upper edge of the strip 44 for bracing and anchoring the heater in place and taking the strain off from the securing bolts. The reason for this construction is that the heater serves as a foot rest and in ordinary service it is subjected to considerable weight and rotative strain. The plate 44 is grounded onto a truck so that in case of a short circuit within the heater a free and unobstructed path to the ground will be provided, thus practically, if not entirely, eliminating danger of fire or personal hazard.

In Figure 5 we have shown a slight modification of the heater, and referring thereto it will be seen that the heater body 46 is provided at both ends with spaced ears 47 apertured for the passage of guard rails 48 which

may, in actual practice, be suitable lengths of pipe. These guard rails extend longitudinally of the heater body and are intended for the purpose of preventing passengers from placing their shoes directly upon the fins or ribs of the heater body. One advantage is that wear on the heater body itself will be prevented and another is that there will be no danger of burning or otherwise injuring or defacing the shoes of the passengers placing their feet upon the heaters.

The above described mechanical construction of the heaters is only by way of illustration, as is the mounting, inasmuch as a different construction and arrangement may be followed. Clearly, it is not necessary that the resistance elements be connected in parallel and there is no limitation desired in this respect. Likewise, as many or as few of the resistance elements may be grouped together as may be found proper so that the ohmic resistance in the groups thereof will correspond to the resistance of the corresponding units of the exterior rheostats. Furthermore, while we have shown and described the preferred embodiment of the invention, we reserve the right to make all other changes and modifications as will widen the field of utility and increase the adaptability of the structure and apparatus, provided such variations constitute no departure from the spirit of the invention or the scope of the claims hereunto appended.

Having thus described the invention, we claim:

1. A car heater comprising an elongated metallic body with a radiating surface, a resistance element located within the body, means for mounting the body beneath the seat of a car, said means including a projection at one end of the body adapted to fit within the usual foot rest socket in the seat pedestal, and attaching ears at the other end of the body adapted to be secured against the metal plate provided on the car wall near the floor.

2. A heater for a car having seats, seat pedestals each provided with an opening for the mounting of a foot rest, the car further having a metal plate on its wall near the floor, the heater comprising an elongated metallic body adapted for disposition beneath a seat and provided at one end with a projection adapted to be received within the foot rest socket, the foot rest being removed therefrom, attaching ears on the other end of the body adapted to be bolted to said metal plate, said second named end of the body having a ledge engaging flatly upon the upper edge of said metal plate, and a resistance element mounted within the body and constituting a heating unit upon passage of current therethrough.

3. In a car having a metal plate secured against the wall adjacent the floor, and having a seat with a pedestal below the same at

- the end most remote from the wall, the pedestal having a socket therein, a heater comprising an elongated metallic body constituting a radiating member and containing a heating unit, a projection extending from one end of the body and fitting within said socket, and means at the other end of the body secured to said metal plate, said body further serving as a foot rest.
- 10 4. In a car having a metal plate secured against the wall adjacent the floor, and having a seat with a pedestal below the same at the end most remote from the wall, the pedestal having a socket therein, a heater comprising an elongated metallic body constituting a radiating member and containing a heating unit, a projection extending from one end of the body and fitting within said socket, and means at the other end of the body secured to 15 said metal plate, said body further serving as a foot rest, said projection being eccentric with respect to the end of the body whereby the heater may be mounted at a relatively low position.
- 15 5. In an electric motor car heating system, exteriorly located rheostats, a plurality of heaters located beneath the car seats, resistances located within the heaters and adapted to serve as control rheostats for the propelling motor of the car, and switch means for 20 selectively cutting a selected number of the exterior rheostats or said resistances into or out of circuit.
6. In an electric motor car heating system, exteriorly located rheostats, a plurality of 35 heaters located beneath the car seats, resistances located within the heaters and adapted and arranged to serve as control rheostats for the car motor, and switch means for selectively cutting the exterior rheostats or said resist- 40 ances into or out of circuit, said switch means being operable to permit certain of the exterior rheostats and interior resistances to remain in the circuit at the same time.
7. In a heating system for an electric car 45 having a propelling motor and control rheostats therefor located exteriorly of the car, said exterior rheostats being arranged in groups, a plurality of heaters located within the car and arranged in groups having an 50 ohmic resistance corresponding to that of the respective groups of exterior rheostats, and switch means for selectively throwing all of said heaters or all of said exterior rheostats into the motor circuit or for throwing a combination of the rheostats and heaters into said circuit. 55

In testimony whereof we affix our signatures.

GEORGE F. WENNAGEL
CARROLL THOMAS.
